CLAIM

The ornamental design for a liquid dispenser, as shown and described.

DESCRIPTION

FIG. 1 is a side perspective view of the new design of a liquid dispenser, showing a microphone in a retracted state; FIG. 2 is another side perspective view thereof; FIG. 3 is a front elevation view thereof; FIG. 4 is a rear elevation view thereof; FIG. 5 is a left side view thereof; FIG. 6 is a right side view thereof; FIG. 7 is a top view thereof; and, FIG. 8 is a bottom view thereof. The broken (dashed) lines show portions of the liquid dispenser that form no part of the claimed design.
